UNITED STATES PATENT OFFICE

JOSEPH GOLDBLATT, OF FOREST HILLS, NEW YORK

FLEXIBLE BRACELET

Application filed August 12, 1930. Serial No. 474,729.

This invention relates to what are known as flexible bracelets, which have a series of sections which together form a band that has flexibility of a limited degree to accommodate any variations in the shape of a wrist, and to yield with the change in conformation of the arm and still maintain practically continuous contact when worn, without causing undue pressure on the arm in any part of the circumference of the bracelet. At the same time such construction of sections and their linkage provide for a firm support for the settings of the stones or jewels, with the desired azured treatment of the sections or panels of the bracelet.

In particular this invention relates to the linking together of the sections of such bracelet, and the particular object is to provide for greater security, to prevent the breaking apart of the sections, and to minimize the wear and repair heretofore most usual, and frequently very costly. That is, the nature of this class of bracelet involves the proper support of gems, and with the entire structure therewith deals with the safeguarding of values from a few thousand to many thousands of dollars. On that account protection against wear and breakage is of vital importance.

In a particular form of my invention the construction is shown in the accompanying drawings, in which:

Fig. I is a perspective, part fragmentary, of a flexible bracelet containing my invention.

Fig. II is a plan view of a few of the sections, broken away in part to show detail.

Fig. III is a section on line III—III of Fig. II.

Fig. IV is a section on line IV—IV of Fig. II.

The flexible bracelet 1 is composed of the numerous similar sections 2—2—2, and these are made in standard sizes, each section being made with one panel for a narrow bracelet, or two or more panels to provide the desired width of bracelet, while the width of each section is uniform usually but may vary.

The sections, whether one or more panels, have on their adjacent edges the straight sections of wire 3—3', which are soldered to the

base 4 of the section, thereby stiffening and strengthening the entire edge of the section where they are attached. At each end of a section there is formed or attached an end portion 5 which has a reentrant portion inwardly projecting to constitute a bezel 6. This bezel 6 may be formed when the entire section is cut with the base 4 and the end member 5, and with portions of the end and base azured to provide for the light to offset the stones or gems, and also to lighten the construction as much as possible and still preserve the rigidity and strength.

The bezel 6 at either end is of such a relative size as to extend inward and present a substantial surface 6', which rests against the skin of the wearer and thereby forms the entire support on the wrist, and becomes the only surface of the bracelet which is subject to wear by the constant motion of the bracelet on the skin of the wearer, and this bezel thereby protects the underside of the bracelet sections against any wear, and particularly protects all of the little hinges or links which hold together the adjacent sections. It is essential primarily for the protection of these links or hinges that my invention provides, and from the advantages resulting therefrom.

These hinges are formed by a small wire 7 which is bent around the wire or wire rods 3—3'. In my construction however, these wires forming the links are arranged so that they encircle the adjacent rods on the juxtaposed sections, but the upper surface of these wires is protected by the bezel 6. As shown in the embodiment illustrated, the bezel 6 protects the link wire upper bend, so that there can be no wearing of the wire 7 by contact and abrasion with the wrist, and this is the particular feature of construction which provides for the safety of the bracelet, to prevent unnoticed wear, and therefore breakage and loss of the entire bracelet, and it also prevents the wearing of the upper section of the link-wire to avoid any weakening of the wire that might be observed, and which therefore would necessitate replacement of the wire before breakage had occurred. In this way my invention provides for the safety against com-

plete loss of a valuable bracelet running into thousands of dollars, or, on the other hand, it prevents the expense of replacement and repair of links.

This link connection is provided by drilling a hole 8 in the base 4, inserting the wire 7 and soldering it firmly. Then the wire 7 is passed through the registering hole 9 in the abutting section of the bracelet and is bent over the rod 3', and then bent around the rod 3. The artisan then clips off the wire and solders it as indicated at 10, or it may also be soldered between the rod 3 and the overhanging bezel 6. This leaves the wire secured by the end soldered at 8, and the end 7' soldered, as shown at 10, or under the overhang of the bezel 6, but leaving it free around the rod 3'. Thus being free about the rod 3' it permits the section attached to rod 3' to turn a limited degree, and therefore provides the limited flexibility of that section with the adjacent section.

The bezel 6 thus provides means for protecting the upper bend 7" of the hinge link 7, so that there will be no wear on this portion of the link, but all of the wear due to contact with the wrist or arm of the wearer is on the surface 6' of the bezel 6. The bezel 6 therefore can be made either integral with the base 4, and can be of any desired thickness in order to withstand the normal wear that is involved in the use of a bracelet of this character.

As the mounting, that is the construction of these sections, is of precious metal, usually platinum, the experience of wear on such material by contact with the skin will of course determine the desired thickness of the bezels 6, and likewise the surface area 6' that is desirable to provide for the longevity of the bracelet. In any event, the construction assures the prevention of accidental loss by the breakage of the links, and enables the artisan to provide a flexible bracelet which may be of any desired linkage construction wholly protected against the normal wear, and therefore a complete safeguard for the bracelet as a whole, and for the valuable gems it may contain, and also eliminate the necessity of frequent repairs of the construction due to heretofore wearing of links or the wearing of any form of construction.

The openwork of the sections and the azuring of the back of the sections for the usual offsetting of stones and gems may vary in many ways, the width of the bracelet may be varied, and the relative thickness of the base of the sections, the mounting for the stones, and the relative size of all parts involved may be varied in many ways, but while I may depart from what I have herein shown and described, what I claim and desire to secure by Letters Patent is:

1. A flexible bracelet having a plurality of sections each forming a base for the sup-

port of gems, interconnecting wire hinge links between the adjacent sections, and a reentrant bezel with a flat area overhanging the connecting links between sections and providing for the wear-resisting contact of the bracelet on the skin. 70

2. In a flexible bracelet, a plurality of sections interconnected by limited flexible hinges of wire encircling cylindrical pintles, each section having an outwardly-facing base and inwardly-facing bezel areas at each end reentrant to overhang the hinge connections between adjacent sections and protect the wire of the hinges from wear. 75

3. In a flexible bracelet, a section for the support of stones on the outer face, reentrant end extensions forming a bezel and forming the internal wearing surface of the section, with wire and rod hinge connections for said sections to an adjacent section of the bracelet having all parts of the hinge positioned under the reentrant extensions forming to overhang of the bezel forming the wearing-contact of the section. 80

4. A flexible bracelet consisting of a plurality of sections having limited hinge or link connections between adjacent sections, including an outwardly-facing base portion, and end portions integrally connected therewith having reentrant flanges forming a substantial smooth interior surface of the bracelet, and hinge connections between the sections positioned in protective relation to the overhanging sections forming bezels on the inner surface of a bracelet including rods secured to the sections and wires encircling the two adjacent rods forming pintles. 95

5. A flexible bracelet consisting of a plurality of sections having a limited hinge or link connection between adjacent section ends, cylindrical rods forming hinged pintles secured along the abutting edges of each section, and bent wire straps secured to one section encircling the hinged pintle on the other section near the end of the pintle, and an overhanging inside bezel on each section protecting the wire strap of the hinge from wear. 105

In testimony whereof, I have signed my name to this application, this 30th day of July, 1930. 110
